United States Patent Office.

JOHN HUGHES, OF NEW BERNE, NORTH CAROLINA.

Letters Patent No. 99,901, dated February 15, 1870.

IMPROVEMENT IN ATTACHMENT FOR LAMP-CHIMNEYS.

The Schedule referred to in these Letters Patent and making part of the same.

To all whom it may concern:

Be it known that I, JOHN HUGHES, of New Berne, in the county of Craven, and State of North Carolina, have invented a new and valuable Improvement in Perforated Glass Chimneys and Globes; and I do hereby declare that the following is a full, clear, and exact description of the construction and operation of the same, reference being had to the annexed drawings making a part of this specification, and to the letters and figures of reference marked thereon.

Figure 1 of the drawings is a front view of my perforated chimney.

Figure 2 is a central vertical section of the same.

Figure 3 is a perspective view of the belt and stop.

Figures 4 and 5 show the manner of attaching the reflectors or shades.

My invention relates to lamp-chimneys that are perforated for the purpose of lighting the lamp, and consists mainly in constructing and arranging therewith a spring band or collar adapted to hold the standard of a reflector or shade, together with a spring and button adapted for opening or closing the aperture in the chimney at will.

The letter A of the drawings designates my lamp-chimney, having the aperture B formed therein near the bottom and opposite the upper end of the wick-tube.

I do not confine myself to any particular size or shape, but design usually to make this aperture a little less than one-half inch in diameter. I may make it of any form, circular or elliptical, and in any manner, whether by cutting, blowing, punching, or molding, or by whatever method will accomplish the object in the most satisfactory manner.

To close this opening, a button or stop, c, arranged with a central projection, s, to fit into the opening, and a rim or flanch, t, is employed. This button may be made of metal, glass, talc, or any other suitable material, and is attached to the spring e, which is pivoted to the spring-belt or collar D, arranged to encircle the base of the chimney. One end of the spring-collar D is arranged to slide in a loop attached to the other end, in such a manner as to render the belt adjustable to a chimney of any size.

By means of the spring e the button c is kept in position to close the aperture in the chimney. When it is desired to light the lamp the button is moved to one side, and a lighted match or taper introduced through the aperture. The lamp may also be extinguished by blowing through the opening.

Sometimes I propose to attach reflectors or shades to the chimney by connecting the standards thereof with the spring-belt or collar D, arranging the fastening in such a manner that when desired the reflector may be readily detached.

What I claim as my invention, and desire to secure by Letters Patent, is—

The spring-band or collar D, provided with the button c, spring e, and socket for the support of a reflector, in combination with the perforated chimney, substantially as and for the purposes specified.

In testimony that I claim the above, I have hereunto subscribed my name, in the presence of two witnesses.

JNO. HUGHES.
